GASEOUS ELECTRIC DISCHARGE LAMP DEVICE

Mari J. Druyvesteyn, Eindhoven, Netherlands, assignor to General Electric Company, a corporation of New York

Application August 16, 1937, Serial No. 159,428
In Germany August 28, 1936

2 Claims. (Cl. 176—122)

The present invention relates to gaseous electric discharge lamp devices generally and more particularly the invention relates to such devices the gaseous atmosphere of which consists of or 5 comprises a metal vapor.

The container glasses used for incandescent lamps and electric discharge lamps containing only a fixed gas are not suitable for use in connection with a discharge lamp containing a 10 chemically active metal vapor because such glasses are quickly discolored by the hot, ionized vapor to terminate the useful life of the lamp. For this reason these discharge devices are made of special glasses, or the inside of the glass wall 15 is covered with substances which are as resistant as possible to the metal vapors. The composition of this glass or coating naturally depends on the particular metal vapor used.

I have observed that occasionally the wall material is more resistant to the metal vapor than to the solid or liquid metal from which the vapor is developed. This is particularly true in the case of a magnesium or thallium vapor discharge device. In such tubes the wall can be made 20 resistant to the metal vapor, but the useful life thereof is shortened by the attack on the wall during operation by the surplus metal in the tube, which is not vaporized, whereby the wall soon loses its mechanical properties and the tube 25 breaks after a short period of operation.

The object of the present invention is to prevent the unvaporized portion of the metal from attacking the container of gaseous electric discharge lamp devices of the above type. Still 30 further objects and advantages attaching to the device and to its use and operation will be apparent to those skilled in the art from the following particular description.

The invention attains its object by providing 35 a condensing surface on the container which surface consists of a material resistant to the effects of said metal in the solid, liquid or vapor state and which is interposed between the unvaporized metal and the wall of the container. This structure prevents the attack of the unvaporized metal 40 on the container glass and the gaseous electric discharge lamp device has a long, useful operating life.

The condensing surface must be at a lower 45 temperature than the other parts of the container during the operation of the device and various means are useful for maintaining the protective layer at the necessary temperature. For example, the heat losses from that part of 50 the container wall covered by the protective layer in relation to the heat losses from the remaining part of said wall are increased. For example, the part covered by the protective layer is made rough or black on the outside to increase 55 the heat radiation locally. The container can 60

also be formed in such a manner that the covered part of the wall is heated less by the discharge than the other parts of the wall. In this case the container is so constructed that the first mentioned part of the wall is farther removed from the discharge path than the last mentioned part.

Preferably, the container is of tubular shape and the protective layer is arranged between the electrodes so that the vaporizable metal is near 10 the discharge path. Preferably, the protective layer extends in the direction of the tube axis and has an oblong form.

The protective layer should be of such thickness that the vaporizable metal cannot penetrate 15 through it. In a magnesium vapor discharge tube a layer of zirconium in the form of a thin foil affixed to the container wall is preferred. One can also use an aluminum oxide layer of appreciable thickness.

In the drawing accompanying and forming 20 part of this specification an embodiment of the invention is shown, in which

Fig. 1 is a side elevational, partly sectional view 25 of a gaseous electric discharge lamp device embodying the invention and

Fig. 2 is a sectional view along the line 2—2 of Fig. 1.

Referring to the drawing the gaseous electric discharge lamp device comprises a tubular container 1 having two thermionic, activated electrodes 2 sealed therein, one at each end thereof. Said electrodes are mounted closely adjacent the respective ends of the container 1 to maintain 30 said ends at an elevated temperature during the operation of the device. Said electrodes 2 each have a pair of current leads and consist of a metal filament, such as a tungsten filament, having thereon a material of high electron emissivity at elevated temperatures, such as barium 35 oxide. The electrodes 2 are heated to an electron emitting, arc discharge supporting temperature by a special heating current or, when desired, said electrodes 2 are heated to such temperature by the discharge incident therat. The container 40 45 1 consists of a glass having a high softening temperature, such as a glass having the following composition:—

	Per cent
SiO ₂	78 50
Al ₂ O ₃	12
CaO	10

This glass is covered on the inside with a magnesium oxide skin. This skin is applied by the following method. The container 1 is first evacuated and heated to about 500° C., then magnesium vapor is passed through the container 1 until a slight attack of the glass is observed without the latter showing a noticeable chemical 55 60

change. Thereupon moist air is admitted into the container 1 and the latter is heated to about 600° C., whereby the magnesium which is on and in the glass surface is oxidized and the slight discoloration of the glass, which is caused by the physical attack of the glass, disappears. This magnesium oxide skin makes the container wall very resistant to magnesium vapor. However at the elevated operating temperature of the container it is less resistant to the magnesium which is not vaporized. In order to avoid this disadvantage, a thin strip 3 consisting of zirconium is applied on the inside of the tube wall, which strip, for instance, is pasted on the container wall with the aid of water-glass and covers only a relatively small part of the wall as shown in the drawing. That part of the outside of the container wall, which lies opposite this zirconium strip, is provided with a black coating 4 consisting for instance of carbon.

The tube contains a rare, starting gas consisting of neon, for example, at a pressure of about 12 mm. Aside from this there is on the zirconium layer 3 in the tube, a quantity of magnesium which during operation furnishes the necessary magnesium vapor.

The black layer 4 locally increases the heat loss so that the zirconium strip is the coldest part of the container enclosing the discharge space. To avoid cold spaces behind the electrodes 2, these are arranged near the ends of the container 1. When desired, the ends of the container are coated on the outside with platinum mirrors to reduce the heat loss of said ends.

Sometimes temperatures can be permitted in the spaces behind the electrodes which are somewhat lower than the lowest temperature of the zirconium strip, if care is taken to avoid distillation of the magnesium over into these spaces behind the electrodes. For this purpose these spaces can, for instance, be closed off with the aid of screens or septums, or the tube wall can be so contracted that practically no magnesium vapor gets into the spaces behind the electrodes.

While I have shown and described and have pointed out in the annexed claims certain novel features of the invention, it will be understood that various omissions, substitutions and changes in the forms and details of the device illustrated and in its use and operation may be made by those skilled in the art without departing from the broad spirit and scope of the invention, for example, the lamp device is mounted in a heat conservator, such as a double walled flask, when desired.

What I claim as new and desire to secure by Letters Patent of the United States, is:—

1. A gaseous electric discharge device comprising a container, electrodes sealed therein, a quantity of vaporizable metal therein the vapor of which is luminosity producing during the operation of the device, the inner wall of said container being resistant to the hot, ionized metal vapor and being subject to attack by the unvaporized portion of said metal, a condensing surface on said container and a material inert with respect to said metal in any state interposed between said surface and the unvaporized portion of said metal and covering said surface to protect said surface from the deleterious effects of said unvaporized metal.

2. A gaseous electric discharge device comprising an elongated, tubular container, electrodes sealed therein at the ends thereof, a quantity of vaporizable metal therein the vapor of which is luminosity producing during the operation of the device, the inner wall of said container being resistant to the hot, ionized metal vapor and being subject to attack by the unvaporized portion of said metal, a condensing surface on said container, said surface extending longitudinally along said container between said electrodes, and a material inert with respect to said metal in any state interposed between said surface and the unvaporized portion of said metal and covering said surface to protect said surface from the deleterious effects of said unvaporized metal.

MARI J. DRUYVESTEYN.
